J. I. RICHEY

MEANS FOR LUBRICATING LEAF SPRINGS

Filed Nov. 18, 1920

Inventor

James I. Richey,

By Arthur H. Ewald,

Attorney

UNITED STATES PATENT OFFICE.

JAMES I. RICHEY, OF CINCINNATI, OHIO.

MEANS FOR LUBRICATING LEAF SPRINGS.

Application filed November 18, 1920. Serial No. 424,832.

To all whom it may concern:

Be it known that I, JAMES I. RICHEY, a citizen of the United States and resident of Cincinnati, in the county of Hamilton and State of Ohio, have invented certain new and useful Improvements in Means for Lubricating Leaf Springs, of which the following is a full, clear, and exact description, reference being had to the accompanying drawings, forming a part of this specification.

The present invention relates to the provision of a suitable housing wherein lubricant may be contained for a leaf spring, and has particular reference to the making of certain improvements over the device described and claimed in my Letters Patent of the United States No. 1,352,915.

In order that leaf springs may give satisfactory and efficient performance at all times, it is necessary that the same be properly lubricated. In my Letters Patent above mentioned, I have described a flexible housing for a leaf spring in which provision is made for the maintenance of a supply of lubricant around the spring. The principal object of the present invention is to further perfect the housing as set forth in said Letters Patent by the extension of the end sections of the housings so that the same will embrace the ends of the spring, thereby better providing against leakage of the lubricant from the housing as well as including the shackle bolts in the system of lubrication provided for the spring.

A further object of the invention is to improve the middle section of the housing as described in said Letters Patent so that the same will embrace the spring clips, and also provide suitable spaces for the retention of lubricant for the middle portion of the spring.

Further objects of the invention will appear from the following detailed description thereof:

In the drawings:

Fig. 1 is a side elevation of a spring provided with a housing constructed in accordance with this invention, portions of the housing being broken away to illustrate features of construction.

Fig. 2 is an elevation similar to Fig. 1,

of the invention, as applied to a spring in inverted position.

Fig. 3 is a section on line 3—3 of Fig. 2. 55

Fig. 4 is a perspective of the middle section of the housing.

Fig. 5 is a perspective of one of the end sections of the housing.

Fig. 6 is a fractional longitudinal section 60 of the invention as disclosed in Fig. 1.

Fig. 7 is a perspective of a grease box to be used in connection with the middle section of the housing. Fig. 8 is a perspective of the lining.

The numeral 1 indicates a portion of the frame of a vehicle, and 2 one of the leaf springs thereof. The spring 2 is secured to the frame member 1 by means of the usual U-bolts or clips 3. 70

The numeral 4 indicates the middle section of a spring housing constructed in accordance with this invention. As clearly shown in Fig. 4 of the drawings, the middle portion of section 4 of the housing is widened as shown at 5 so as to embrace the spring clips 3. The ends of the middle section 4 are provided with perforations 6. 75

When applied to an inverted spring, as illustrated in Fig. 2, the bottom of section 4 of the housing is also provided with perforations to permit the passage of the ends of the clips 3.

Arranged to be secured to the middle section 4 of the housing are end sections 7, 85 same being provided with slots 8 for rivets or bolts 9, which also extend through the perforations 6 of the middle section; the end sections are thus pivotally and slidably secured to the middle section. The end sections 7 are shaped, as shown in Fig. 5, so as to embrace the bottom and sides of the spring, and are provided with flanges 10 which extend outwardly from the upper edges thereof throughout the greater portion of their lengths. 90

The flanges 10 are provided with perforations 11 for bolts or rivets by means of which cover plates 12 are secured to the end sections. The sections 7 are provided at 100 their ends with cupped extensions 13 arranged to embrace the spring bolt eyes at the ends of the spring. Beyond the outer ends of the flanges 10 of the sections 7, said

- sections are provided with ears or lugs 14 within which rollers 15 are mounted. The rollers 15 are arranged to bear against the upper side of the spring near its ends.
5. Interposed between the housing comprising the middle section 4 and end sections 7 and the spring is a felt or other suitable lining 16, the same being illustrated in perspective in Fig. 8 of the drawings. The top 10 lining 17 is secured between the cover plates 12 and the flanges 10. The lining 16 is cupped to embrace the ends of the spring.
- Arranged to be inserted inside the widened portions 5 of the middle section 4 at the sides 15 of the spring 2 between clips 3 are grease boxes 18, which are arranged to contain a renewable supply of lubricant for the middle portion of the spring. Preferably at the points of highest elevation on the housing are lubricant cups 19.
- From the foregoing description the nature and value of the present invention will be apparent. When provided with a housing constructed in accordance with this invention it will be seen that a spring may be kept at all times thoroughly lubricated. By reason of the slotted connection between the middle and end sections, provision is made for the necessary pivotal and longitudinal 30 movements of the housing during the spring flexions. The cupped extensions of the housing provide means whereby the spring bolts, by means of which the springs are secured to the shackles, may be at all times immersed 35 in a suitable lubricant. The rollers 15, which bear upon the upper sides of the spring near the ends, cause the housing during its movements to ride freely, and thus quietly and without unnecessary wear to accommodate itself to the spring movements. As will be obvious, the lining 16 serves to prevent leakage, and this end is further attained by the cupped extensions 13 of the housing which retain the lubricant that 40 would otherwise be lost, and this is used as above set forth.
- Having thus fully described my invention, what I claim as new and desire to secure by Letters Patent is:
50. 1. A device of the character specified, comprising in combination with a leaf spring, a housing for said spring, said housing comprising a middle section, said middle section having a widened portion intermediate its length, end sections pivotally secured to said middle section, cover plates for said end sections, and lubricant boxes arranged to be inserted into the widened portion of said middle section at opposite sides of the spring.
60. 2. A device of the character specified, comprising in combination with a leaf spring, a housing for said spring, said housing comprising a middle section, said middle section having a widened portion intermediate its 70 length, end sections pivotally secured to said middle section, said end sections having cupped extensions arranged to embrace the spring bolt-eyes, cover plates for said end sections, and lubricant boxes arranged to be inserted into the widened portion of said middle section at opposite sides of the spring.
3. A device of the character specified, comprising in combination with a leaf spring 75 and spring clips for securing the same to a vehicle frame, a housing for said spring, said housing comprising a middle section, said middle section having a widened portion arranged to embrace said clips so as to leave a space between the spring and housing and between said clips, end sections pivotally secured to said middle section, cover plates for said end sections, and lubricant boxes arranged to be inserted in the space 80 formed by said middle section between said clips.
4. A device of the character specified, comprising in combination with a leaf spring 85 and spring clips for securing the same to a vehicle frame, a housing for said spring, said housing comprising a middle section, said middle section having a widened portion arranged to embrace said clips so as to leave a space between the spring and 90 housing and between said clips, end sections pivotally secured to said middle section, said end sections having cupped extensions arranged to embrace the spring bolt-eyes, cover plates for said end sections, and lubricant boxes arranged to be inserted in the space 95 formed by said middle section between said clips.
5. A device of the character specified, comprising in combination with a leaf spring, a 100 housing for said spring, said housing comprising a middle section, end sections pivotally secured to said middle section, rollers mounted near the outer ends of said end sections and arranged to bear upon the upper side of the spring, and cover plates for said 105 end sections.
6. A device of the character specified, comprising in combination with a leaf 110 spring and spring clips for securing the same to a vehicle frame, a housing for said spring, said housing comprising a middle section, said middle section having a widened portion arranged to embrace said clips so as to leave a space between the spring and housing 115 and between said clips, end sections pivotally secured to said middle section, rollers mounted near the outer ends of said end sections and arranged to bear upon the upper side of the spring, cover plates for said end sections, 120 and lubricant boxes arranged to be inserted in the space 125 formed by said middle section between said clips.
7. A device of the character specified, comprising in combination with a leaf spring 130

and spring clips, for securing the same to a vehicle frame, a housing for said spring, said housing comprising a middle section, said middle sections having a widened portion arranged to embrace said clips so as to leave a space between the spring and housing and between said clips, end sections pivotally secured to said middle section, said end sections having cupped extensions ar- ranged to embrace the spring bolt-eyes, 10 rollers mounted near the outer ends of said end sections and arranged to bear upon the upper side of the spring, cover plates for said end sections, and lubricant boxes arranged to be inserted in the space formed 15 by said middle section between said clips.

JAMES I. RICHEY.
